(57) **CLAIM**

The ornamental design for a computer, as shown and described.

DESCRIPTION

FIG. 1 is a top, rear, right-side perspective view of a computer in accordance with my new design;

FIG. 2 is a front elevational view of the computer shown in FIG. 1;

FIG. 3 is a rear elevational view of the computer shown in FIG. 1;

FIG. 4 is a right-side elevational view of the computer shown in FIG. 1;

FIG. 5 is a left-side elevational view of the computer shown in FIG. 1;

FIG. 6 is a top plan view of the computer shown in FIG. 1;

FIG. 7 is a bottom plan view of the computer shown in FIG.

1.

FIG. 8 is a top, rear, left-side perspective view of the computer shown in FIG. 1; and,

FIG. 9 is a right-side elevational view of the computer shown in FIG. 1, in an open configuration.

The broken lines immediately adjacent the shaded areas represent the bounds of the claimed design while all other broken lines are directed to environment and are for illustrative purposes only; the broken lines form no part of the claimed design.
